US0D1067258S

(12) **United States Design Patent** (10) Patent No.: **US D1,067,258 S**
(45) Date of Patent: ** Mar. 18, 2025

(54) **ELECTRONIC DEVICE WITH GRAPHICAL USER INTERFACE**

(71) Applicant: **Apple Inc.**, Cupertino, CA (US)

(72) Inventors: **Taylor Gerard Carrigan**, San Francisco, CA (US); **Kevin Will Chen**, Cupertino, CA (US); **Alan C. Dye**, San Francisco, CA (US); **Aled Williams**, Llandeilo (GB); **Christopher I. Wilson**, San Francisco, CA (US)

(73) Assignee: **Apple Inc.**, Cupertino, CA (US)

(**) Term: **15 Years**

(21) Appl. No.: **29/800,875**

(22) Filed: **Jul. 23, 2021**

Related U.S. Application Data

(63) Continuation of application No. 29/777,266, filed on Apr. 5, 2021, which is a continuation of application No. 29/663,058, filed on Sep. 11, 2018, now Pat. No. Des. 915,436.

CLAIM

The ornamental design for an electronic device with graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing the claimed design; FIG. 2 is another embodiment thereof; and,

FIG. 3 is a front view of an electronic device having a display screen with graphical user interface, showing a third embodiment of the claimed design.

The broken lines in the figures show a display screen or portion thereof, or an electronic device having a display screen, and form no part of the claimed design.
